(Cl. D91—3)

To all whom it may concern:

Be it known that I, Jacques Stanitz, a citizen of the United States, residing at Warren, in the county of Trumbull and State of Ohio, have invented a new, original, and ornamental Design for a Spray Nozzle, of which the following is a specification, reference being had to the accompanying drawing, forming part thereof.

Figure 1 is a side elevation of a spray nozzle showing my new design;

Fig. 2 is a bottom plan view thereof;
Fig. 3 is an end elevation thereof; and
Fig. 4 is a perspective view thereof.
I claim:
The ornamental design for a spray nozzle, substantially as shown.

JACQUES STANITZ.
